UNITED STATES PATENT OFFICE.

CHARLES JOHN GLASEL, OF NEW YORK, N. Y., ASSIGNOR, BY MESNE ASSIGNMENTS,
TO LUISE HAGEN GLASEL, OF NEW YORK, N. Y.

LOADING AND UNLOADING MACHINE.

1,411,342.

Specification of Letters Patent.

Patented Apr. 4, 1922.

Application filed July 19, 1917. Serial No. 181,652.

To all whom it may concern:

Be it known that I, CHARLES JOHN GLASEL, a citizen of the United States of America, residing at New York, in the 5 county of New York and State of New York, have invented certain new and useful Improvements in Loading and Unloading Machines, of which the following is a specification.

10 My present invention relates to improvements in loading and unloading machines, especially adapted for automatically and mechanically transporting or transferring hides and skins, and for charging and dis- 15 charging receptacles with such hides and skins, such as tanning machines, dye vats, drying lofts, etc.

The invention is designed primarily for the purpose of providing a new step in the 20 handling of hides and skins during the process of tanning, and especially for the purpose of eliminating hand labor, to a great extent, in which the laborers are exposed to a tiresome and unsanitary work, 25 thus reducing immensely the cost of labor and production of tanned materials.

The invention mechanically considered 30 consists essentially of a main portable truck, for conveying or transporting skins and hides from place to place for various treatments during the process of tanning, and also contemplates an elevator structure 35 on the truck upon which an auxiliary carriage or carrier is movable, and an extensible track way by which the carrier may be projected to proper position where a hide-supporting member carried by the carrier may 40 be either loaded or unloaded from the carrier as the case may be, and the invention further consists in certain novel combina- 45 tions and arrangements of parts as will be hereinafter more fully described and claimed.

In the accompanying drawings I have 50 illustrated one complete example of the physical embodiment of my invention, constructed and arranged according to the best mode I have so far devised for the practical application of the principles of my invention, and while I shall hereinafter refer to the device in connection with the handling of hides and skins, it will readily be understood that other articles or objects may be handled equally well by the machine.

55 Figure 1 is a side elevation of a machine

embodimenting my invention, with the elevator in lifted position in dotted lines, and showing the barrel of a tanning machine to illustrate the relation between the loading machine and the tanning machine.

60 Figure 2 is a side elevation of the loading machine, with the carrier projected and in the act of unloading a supporting member for the hides in the barrel of the tanning machine.

65 Figure 3 is a view in side elevation of the upper frame portion of the portable truck showing the carrier, elevated, and in position to be projected to carry a skin or hide beyond the forward end of the truck.

70 Figure 4 illustrates the extended track way and projected carrier in the act of placing skin supporting members in a loft.

75 Figure 5 is a transverse sectional view through the machine, carrier, and hide supporting member, showing the hides supported thereby, and showing also the tanning machine barrel or receptacle in cross section.

80 Figure 6 is an enlarged top plan view of one end of the truck illustrating the operating or driving mechanism.

85 Figure 7 is an end view of the portion of the machine shown in Figure 6.

Figure 8 is a sectional view of the elevator, carrier, and a portion of the hide supporting member.

90 Figure 9 is a top plan view of the suspending bars or rods forming part of the hide supporting member.

95 Figure 10 is a transverse sectional view of the hide supporting member.

Figure 11 is a top plan view of the machine, with the hide suspension bars removed.

100 In the preferred form of the invention as illustrated in the drawings, the portable truck is made up of a metallic horizontal base frame 1 from which rise the two pairs of upright corner posts 2 and 3. The upper ends of these posts 2 and 3 are connected in pairs by longitudinally extending side arms 4 and 5, the posts and side bars being composed of angle irons. The upper and lower longitudinal members of the frame are rigidly bolted or riveted with the uprights or posts, and the entire structure is supported on the four wheels or casters 6.

105 The truck is provided with four corner screws bars, 7, 7, 7, 7, rising from the lower

members of the frame where they are supported in bearings 8, and at the upper end of the frame additional bearings or brackets 9 are provided so that these screw bars 5 may be revolved. The screw bars are revolved through the medium of a driving shaft 10 supported in journal bearings 11 on a rear platform or extension of the frame as indicated at 12. Power is applied to the 10 driving shaft through the gear 13 and pinion 14, the latter on an actuating shaft 15, which may be revolved from a suitable source of power through the sprocket wheel 16.

15 The driving shaft 10 is geared to drive the two counter-shafts 17 and 18, in unison, and these countershafts extend along the longitudinal sides of the truck frame, being supported in journal bearings 19, and the driving shaft 20 is coupled to the countershafts through the bevel gears 20 and 21, the gear couples being located at the ends of the driving shaft as best seen in Figure 6. Each countershaft is provided with a pair of 25 worm screws, as 22 23, and these respective worm screws engage the worm wheels 24, four in number and one each fixed on a screw bar or upright threaded post 7, so that when the driving shaft is actuated the two countershafts impart rotary motion to the screw bars through the medium of the bevel gear couples and the screw couples as described.

Through the rotation of these four screw bars the elevator is operated, and this elevator comprises a frame, open at its front, horizontally disposed, and preferably of flat metallic side bars 25, having at the four corners of the rectangular shaped frame the fixed nuts 26 each threaded for a screw bar 7, and each firmly bolted or riveted to the elevator frame. Thus it will readily be seen that when these four screw bars are revolved in unison, the elevator will be lifted or lowered, depending upon the direction of rotation of the screw bars.

The two bars 25 of the elevator frame form rails or tracks, positioned, always, in a horizontal plane, and an upwardly inclined, fixed rail 26' forms a continuation or extension of each of these rails, these inclined rails being riveted or bolted to the horizontal side rails of the elevator, and, of course the fixed rails or inclined rails move bodily with the horizontal rails as the elevator is operated. 50 The rails may be elongated, and to accomplish this purpose I provide an extension rail 27 for each of the inclined rails 26', the extension rails being adapted to telescope or slide within grooved guideways located at 55 the inner sides of the inclined rails 26', and each provided with a horn or bumper 28 at its extreme end. The slide rails or extension rails are projected from the stationary rails of the elevator by means of a pair of 60 chains 29, one at each side of the elevator,

attached at 30 to the carriage 31, passed over an idler pulley 32 and a second pulley or sheave 33 both journaled on the stationary part of the elevator frame, and then the chains pass to the rear of the machine and each over a drum 34, which drums are carried on shaft 34' journaled below the rear platform 35 which joins the side bars 25 of the elevator, at the rear of the machine. The drums may be revolved from the driving shaft 36 through sprocket gearing indicated at 37 in Figure 11 from a conventional clutch mechanism shown in said figure, to wind the chains on the drums, and the winding of the chains of course draws the carriage, as to the 70 right, in Figure 2. The carriage is provided with four wheels arranged in pairs 38, 38, on axle 39, and 40, 40 on axle 41. Thus when the slide rail is projected, or rather when the carriage is made to project the rail, the 75 winding of the chain on the drum first draws the carriage along the rails 25, 26' until the front wheels 40 encounter the horn shaped bumpers 28 and ride up on them as shown best in Figure 2, then the continued pull of 80 the chains causes the extensible frame or rails 27 to slide upwardly and outwardly, with the wheels 40 supported on the bumpers and the wheels 38 rolling over the inclined rail 26' until the extensible rails and carriage reach the projected position in Figure 2.

The carriage 31 is joined at the front by the cross arms 42 and at the rear by the cross brace 43, and it will be understood that the 100 axle 39 at the rear may extend across from side bar to side bar of the frame, but the axles for wheels 40 are stub axles 41 in the respective side bars of the frame, so that a hide or skin 44 may be carried between these 105 side bars of the carriage frame. The hides or skins are supported on a suspending member which I shall term a carrier, which comprises two end bridges 45, 45 formed with end arms 46 and sharp pins or studs 47, and between these two bridges are supported a plurality of suspension bars or rods 48 each of which is socketed to fit over the pins on the bridges, and the hides or skins are suspended from these rods or bars. The bridges 45 of the carrier are rigidly supported on the carriage 31, and the suspension bars 48 as illustrated in Figure 2 of the drawings, are designed to be suspended in the rotary barrel 49 forming part of a tanning machine. 115 One head of the barrel is open for admission of the projected machine, and both heads of the barrel are provided with supporting means so that the bars 48 may be suspended longitudinally of the barrel at the inner periphery thereof, and when the barrel is rotated the hides or skins on the bars 48 are carried bodily around with the barrel. The machine of the invention is so constructed 120 that it will manipulate the carrier and sus- 125 130

pend the hide supporting bars in the rotary barrel. The first part of the operation has been accomplished in full lines in Figure 2, and the forward ends of the bars 48 are supported on a ring 50 at the distal end of the barrel, while the second part of the movement is indicated in dotted lines in Figure 2, where the bars are supported between the ring 50 and a similar ring 51 at the proximate end of the barrel.

The proximate end of the carrier is lifted from position in full lines Figure 2 by a pair of lifting jacks supported on the elevator, which jacks lift the carriage, or rather one end of the carriage and swing it upwardly on the wheels 40 as pivot points.

These lifting jacks are operated in unison from the driving shaft 36 at the rear of the elevator which has a pinion 52 thereon engaging the gear 53 on the transverse shaft 54 beneath the platform 35. Shaft 54 extends from end to end of the platform and has a pair of bevel gears 55 which engage gears 56 on the lateral shafts 57 journaled in bearing brackets 58 on the elevator. At their opposite ends these shafts are provided with bevel gears 59 which engage bevel pinions 60 on the vertical screw bars 61 supported in bearings 62 on a leg 63 of the elevator. On each screw bar is a threaded nut 64 formed with an arm 65 which supports a lifting lever 66 that is slidable in bearings 67 on the elevator, and at its upper end each lever is provided with a hooked or curved seat 68 adapted to engage up under the two ends of the axle 39 of the carriage. Now when the jacks are operated as described it will readily be seen that the carriage will be swung on the front wheels as a pivot, the forward end being lowered and the rear end lifted so that the proximate ends of the hide bearing arms are lifted and moved endwise into place as before indicated. The hide bearing arms are of proper length to permit endwise shifting when they are being lifted above the bars 50 51, and are of suitable length to rest on said bars. In order to withdraw the projected part of the machine from the barrel, the jacks may be lowered, or the elevator may be bodily lowered, the carriage permitted to run down its inclined tracks and the extension or slide frame withdrawn or retracted, as by a pull chain, not shown.

In Figure 4 the machine is manipulating the hides and their carriers so that the hides are suspended in a loft, between the two horizontal supports 69, 70, the operation, however, being practically the same as when the hides are placed in the barrel or receptacle of the tanning machine for treatment.

In Figure 9 a sectional form of the hide supporting bar or rod is illustrated, this form also being shown in Figure 5. Here the lower section 71 has sockets 72 to fit

over the pins or studs 47 on the bridge and the intermediate section 73 has double end spikes 74 projecting from its top and bottom to engage sockets 75 in the lower section and similar sockets 76 in the upper section. The hides or skins are suspended from the bars as indicated in Figure 5, being retained between the upper section and intermediate section and the lower section and intermediate section respectively.

The carrier which supports the bundle of hides or skins may be of various constructions, and the use of the machine may be varied greatly, but the operation remains the same, and while I have described the machine in connection with the treatment of hides, it will readily be understood that other articles or objects may be manipulated or handled by the machine.

Changes may also be made in the construction of the machine, within the scope of my claims without departing from the spirit of my invention, and all such changes are contemplated.

In operating the machine in the process of treating hides and skins, with the loaded carrier supported on the carriage, the apparatus is brought to position of Figure 1, ready to suspend the carrier and its hides in the tanning machine barrel 49. The elevator is lifted to the position indicated in dotted lines Figure 1, and then the extensible frame, carriage, its carrier and the bundles of hides are projected into the tanning barrel by operating the chain or wire rope 29. The carriage is so manipulated, by the movement of both the elevator and the projecting apparatus, that the upper ends of the hide supporting bars are located in their suspension devices in the barrel, and then the lower end of the carriage is tilted upwardly by means of the elevating jacks so that the proximate ends of these hide supporting bars are emplaced, as shown in dotted lines Figure 2. After the carrier has been properly deposited, the jacks are lowered, the carriage will roll down its incline, and then the carriage and extensible frame are retracted.

No claim is made herein to the particular form of carrier or hide supporting bars, nor to the special manner of loading tanning machines, or depositing the carriers in lofts, for the invention contemplates all uses to which the machine is applicable outside of, as well as inside of the tanning art.

By the utilization of my improved machine and method of handling hides and skins, the hides and skins may be quickly adjusted while in suspension on the carrier to desired position, as for instance, a flat suspension or a folded one, or partly suspended, or hose shape, a single hide or a whole pack, with the hides and skins overlapped at their bases, or enveloping such

hides and skins in such a bag form as may be designed by the operator.

What I claim is:—

1. The combination in a machine as described including a portable truck, of an elevator, a carriage on the elevator and operating means on the elevator for said carriage, an extensible supporting frame on the elevator, and means for actuating said carriage whereby the frame is extended while supporting the carriage.

2. The combination with a supporting structure of an elevator, a carriage thereon, an extensible frame on the elevator, and means for projecting the combined extensible frame and carriage, and means for tilting the carriage while supported on the extended frame.

3. The combination with a portable truck, an elevator thereon and a carriage on the elevator, means for projecting the carriage and supporting it beyond the truck, and means for tilting the supported carriage.

4. The combination with a supporting structure and an elevator thereon, of a carriage, means for bodily projecting and supporting the carriage, and means for tilting the thus supported carriage.

5. The combination with a supporting structure and a carriage thereon, of an extensible frame, means for moving the carriage whereby the frame and carriage are projected as described, and means on said structure for tilting the projected carriage.

6. The combination with a supporting structure and a carriage thereon, of an extensible frame, means for moving said car-

riage whereby the frame and carriage are projected as described, a carrier on the carriage, and means for tilting the projected carriage to dispense with the carrier. 40

7. The combination with a supporting structure, of a carriage thereon, an extensible frame and means for projecting said carriage whereby the frame is extended, and 45 lifting jacks on said structure for tilting said carriage.

8. The combination with a supporting structure, of an extensible and tilttable member, a normally disengaged lifting link on the structure to engage said member, a screw bar and a movable nut thereon, and a lever arm on said nut engaging said link, for the purpose described. 50

9. The combination with a supporting structure and a carriage thereon, of an extensible frame and means for projecting it from the structure whereby the carriage is supported partly on the structure and partly 60 on said frame, and means on the structure 65 for engaging a portion of the carriage to elevate it, as described.

10. The combination with a supporting structure and a carriage thereon having wheels and axles, of an extensible frame and means for projecting it from the structure whereby the carriage is supported on the structure and frame, and means on the structure for engaging the axle of the carriage to swing the carriage on a pivot with its fulcrum point on the extensible frame. 70

In testimony whereof I affix my signature.

CHARLES JOHN GLASEL.
